(57) **CLAIM**

The ornamental design for a video conference endpoint, as shown and described.

DESCRIPTION

FIG. 1 is a front, right perspective view from above of a video conference endpoint, according to the present invention; FIG. 2 is a top plan view of the video conference endpoint, of FIG. 1; FIG. 3 is a bottom plan view of the video conference endpoint, of FIG. 1; FIG. 4 is a front elevation view of the video conference endpoint, of FIG. 1; FIG. 5 is a rear elevation view of the video conference endpoint, of FIG. 1; FIG. 6 is a right side elevation view of the video conference endpoint, of FIG. 1; FIG. 7 is a left side elevation view of the video conference endpoint, of FIG. 1; and, FIG. 8 is another front, right perspective view from above of the video conference endpoint, of FIG. 1. Any portions shown using dashed lines are for illustrative purposes only and form no part of the claimed design.

1 Claim, 8 Drawing Sheets
